UNITED STATES PATENT OFFICE.

CONRAD ADAMI, OF BOSTON, ASSIGNOR TO JAMES W. TUFTS, OF MEDFORD,
MASSACHUSETTS.

APPARATUS FOR DISPENSING SODA-WATER.

SPECIFICATION forming part of Letters Patent No. 316,594, dated April 28, 1885.

Application filed December 12, 1884. (No model.)

To all whom it may concern:

Be it known that I, CONRAD ADAMI, a citizen of the United States, residing at Boston, in the county of Suffolk and State of Massachusetts, have invented certain Improvements 5 in Apparatus for Dispensing Soda-Water, &c., of which the following is a full, clear, and exact description, reference being had to the accompanying drawings, making part of this 10 specification, in which—

Figure 1 is a perspective view of my improved apparatus for dispensing soda-water, &c. Fig. 2 is a vertical section of the same. Fig. 3 is a vertical section through the center 15 of one of the shells or cups of the cooler and parts adjacent thereto. Fig. 4 is a perspective view of one of the sirup-cans removed from the apparatus. Fig. 5 is a section through one of the couplings of the supply-pipe leading 20 from the fountain to the draft-tube. Fig. 6 is an elevation of a portion of the front of the apparatus, with the sirup-cans removed and their covering-doors partially broken away.

My invention relates to certain improvements 25 in apparatus for dispensing soda-water, &c.; and it consists in certain novel combinations of parts, as hereinafter set forth and specifically claimed.

In the drawings, A represents the casing of 30 an apparatus for dispensing soda-water, &c. Within the upper portion of this casing A is fitted the removable box or ice-chamber B, provided with the usual waste-pipe, b, and having a vertical passage, c, between it and the casing A through which extends the supply-pipe d, leading from the fountain (not shown) to the cooler, which latter communicates 35 through a pipe, a, with the draft-tube C at the front of the apparatus. The lower portion of the casing A is provided with a horizontal partition or bottom, e, from the upper surface of 40 which rise a series of vertical plates, f, forming a series of horizontal chambers or cells, g, having their mouths or front ends open by reason of a portion of the side of the casing A opposite thereto being removed. Within 45 these cells or chambers g are placed the horizontal sirup cans or receptacles D, of the form seen in Figs. 1 and 4, which are adapted to be

slid horizontally into and out of their cells g 50 from the front of the apparatus by taking hold of the sirup gates or faucets h, which latter remain at all times permanently attached to the cans D, and are withdrawn and replaced therewith, no disconnecting or connecting of 55 these faucets with the cans being required in the operation of removing or replacing the same within the apparatus, whereby time and labor are saved, and much inconvenience avoided whenever it becomes necessary to remove these cans for cleansing or other purposes. The tops of the sirup-cans D are open, as seen at i, which admits of their being easily filled when partially drawn out, the operation of 60 filling being more conveniently performed than 65 where it is necessary to lift the heavy marble cover of the casing to gain access to the sirup-cans, as heretofore. Each cell or chamber g is provided with a cover or door, k, preferably pivoted at its upper end to the casing of 70 the apparatus, and adapted to drop by its own gravity over the open mouth of its cell, and thus conceal the same and the front end of the can D within it, whereby a neat and finished 75 appearance is given to the front of the apparatus.

At the bottom of each door k is an open slot or notch, l, Fig. 1, within which fits the neck or shank m of the faucet h, thus enabling the door to extend down sufficiently to entirely 80 cover the mouth of the cell g, the slot falling directly over the neck m as the can D is pushed into its cell, while the shoulder 10 of the faucet comes into contact with the metal at the sides of the slot l and keeps the door or 85 cover snugly and securely in place.

At the bottom of the front of each cell or chamber g is a square slot or notch, 8, into which fits the square shank m of the sirup-can faucet h, which is thus prevented from 90 becoming unscrewed while being operated.

Each door k has preferably engraved upon it the name of the sirup contained in the can in line therewith, and these doors may be hinged or pivoted at their upper ends, as 95 shown, or otherwise applied in such manner as to admit of their being dropped down over the mouths of the cells or chambers g.

It is obvious that the vertical plates *f* may be dispensed with, if desired, leaving a single wide chamber for the reception of the several sirup-cans.

5 G is the cooler, which is located within the ice-chamber of the apparatus in any suitable position, and is connected by pipes *p* *a* with the supply-pipe *d* and draft-tube *C*. This cooler is composed of a series of concavo-concave shells or flat cups, *r*, composed of copper lined with tin, and tightly soldered at their edges to a flat plate, *s*, of block-tin, which is strengthened and rendered sufficiently stiff and rigid by a backing-plate, *t*, of brass or 15 other hard metal secured thereto.

Suitable pipes or passages, *v*, are provided for connecting the several vessels *r*, in order that the liquid to be cooled may pass through the entire series on its way to the draft-tube.

20 As the solder at the edges of the shells *r* would not form a sufficiently-reliable means of holding the said shells to the plates to enable the vessels to resist the pressure of the gas contained in the aerated liquid passing 25 through them without leakage, I provide an additional fastening consisting of a bolt, *a'*, the head of which rests on the top of the shell *r*, its shank passing down through a short block-tin tube or sleeve, *b'*, Fig. 3, soldered 30 within an aperture at the center of the shell, and extending down through the tin-plate *s*, to which it is also soldered to form a tight joint at this point.

Beneath the hard-metal backing *t* a nut, *c'*, 35 is screwed over the end of the shank of the bolt *a'* by means of which its head is drawn firmly down onto the outside of the shell *r*, which is thus enabled to resist any pressure to which it may be subjected without liability of 40 leakage around the edges where it is soldered to the plate *s*. It will be seen that the shells or vessels *r* are very shallow, and offer a large area of cooling-surface, whereby the liquid passing through them becomes rapidly chilled, 45 while the entire cooler is exceedingly compact and consequently occupies very little space within the cooling-chamber, which is thus enabled to contain the maximum quantity of ice.

The portion 12 of the supply-pipe *d* which 50 is attached to the apparatus is connected beneath the counter with the portion 20, leading

to the fountain by means of a coupling, *H*, consisting of a male portion, *e'*, within which the end of the portion 12 of the pipe is fitted and immovably secured thereto by solder, and 55 a nut or female portion, *f'*, adapted to swivel, as usual, on the end of the portion 20 of the supply-pipe. The male portion *e'* is provided with a bracket, *g'*, made integral therewith and having apertures *i'*, to enable it to be 60 screwed to any convenient surface beneath the counter, as seen in Fig. 1, by which means this portion of the coupling is held rigidly in place and the soft block-tin pipe *d*, which is secured immovably thereto, is thus effectually 65 prevented from being twisted and injured in the operation of putting together the two portions of the coupling and tightening them up.

What I claim as my invention, and desire to secure by Letters Patent, is—

70 1. In an apparatus for dispensing soda-water, &c., the combination, with the casing *A*, provided with a series of separate horizontal chambers or cells, *g*, having open mouths accessible from the side of the apparatus, of the horizontal removable sirup-cans *D*, having gates or faucets *h* projecting from their front ends, and adapted to be slid into and out of the said horizontal chambers or cells *g* from the side of the apparatus, and the covers or doors 80 *k*, pivoted at their upper ends and adapted to drop down over the front ends of the sirup-cans to conceal the same, substantially as described.

2. The combination, with an apparatus for 85 dispensing soda-water, &c., provided with horizontal removable sirup-cans *D*, adapted to slide in and out from the side of the apparatus, and having gates or faucets *h* projecting from their front ends, of the covers or doors *k*, 90 pivoted at their upper ends and having open slots *l* at their lower ends to fit over the necks of the sirup gates or faucets, and adapted to drop down over the front ends of the sirup-cans to conceal the same, substantially as set forth. 95

Witness my hand this 4th day of December, A. D. 1884.

CONRAD ADAMI.

In presence of—

P. E. TESCHEMACHER,
W. J. CAMBRIDGE.
